UNITED STATES PATENT OFFICE.

AMBROSE ELVIN ZIERICK, OF NEW YORK, N. Y.

RADIOCOIL.

Application filed April 13, 1925. Serial No. 22,786.

This invention relates to toroidal air core coils, and a method of making the same. Heretofore a great deal of trouble has been experienced in the manufacture of toroidal coils, due to the fact that the inner periphery of the coils where the portions of the loops of the wire were crowded together disclosed a decided weakness, the strands forming the coils at this point becoming readily displaced and the function of the device impaired. Furthermore, the delicacy of the structure produced by the weaving of the wire on supports, which precluded any degree of rigidity or reinforcement, aided materially in the gradual disintegration of the coils. The loops at the inner periphery being laid in juxtaposition tended to provide a larger coil for the quantity of wire required than was necessary.

It is an object of the present invention to provide a coil in such a manner that the woven strands of wire, more particularly at the inner periphery of the core of the coil, will be overlapped and intertwined to an extent that there will be no possibility of the wires or coil becoming disassociated.

Another object of the invention is the provision of a coil formed of wire woven on uniformly spaced flexible strands of non-conducting material and a reinforcing strand spaced from one of the strands so that an alternate pair of loops of the wire will be disposed upon one side of the reinforcing strand and embraced upon opposite sides by loops of the wire, one of the last mentioned loops passing between the reinforcing strand and its adjacent strand, while the other loop is disposed outwardly and around the adjacent strand.

A further object of the invention is the provision of a method of forming toroidal coils, in which a wire is interwoven in such a manner with spaced supporting strands and a co-operating reinforcing strand spaced from one of the supporting strands that a cylindrical formation will be produced, with the portions of a pair of loops of the wire being located inwardly of the reinforcing strand and portions of wire continuing from the loops crossing alternately one on each side of their portions of the wire, while the loops of the continued portions adjacent the inwardly disposed portions are located outwardly of the reinforcing strand and the adjacent supporting strand.

A still further object of the invention is

the provision of a toroidal coil, in which a wire is interwoven with a plurality of spaced supporting strands and a reinforcing strand spaced from one of the supporting strands, and in which the portions of the wire adjacent the inner periphery of the toroidal coil are disposed away from the periphery, with the adjacent portions of juxtaposed loops projecting outwardly from the first mentioned loops, so that when the coil is formed the portions of the loops at the inner periphery may overlap each other and thereby permit a decrease in the diameter of the inner periphery.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a plan view of a toroidal coil constructed according to the principles of my invention.

Figure 2 is a transverse vertical section of one form of the coil.

Figure 3 is a side view of certain portions of the loops of the wire showing the method of weaving the wire with the supporting strands.

Figure 4 is a transverse vertical section of the preferred form of my invention.

Figure 5 is a side view of a section of the coil showing the method of weaving the wire with the supporting strands for producing the construction disclosed in Figure 4.

Referring more particularly to the drawings, 1 to 5, inclusive, respectively designate the spaced supporting strands upon which the insulated wire 6 is woven. A reinforcing strand 7 is spaced from any one of the supporting strands, such as 4, a sufficient distance to permit the insertion of the loops of the wire 6. The supporting and reinforcing strands are held in the usual manner in spaced relation so that the wire may be interwoven with the strands.

Referring more particularly to Figure 2, the method of weaving is as follows: The wire 6 is carried downwardly around strand 4 to form a loop 8 in substantially close

contact with said strand, and upwardly and inwardly of strand 5 to form a loop 9, outwardly and around strand 1 forming a loop 10, and inwardly of strand 2 forming a loop 11, downwardly and outwardly of strand 3, as shown at 12, and between strands 4 and 7. The strand is then carried outwardly and around strand 5, as shown at 13, instead of inwardly, as spaced from the loop 9 by 5 the strand 5, so that the loops 9 and 13 thus formed embrace opposite sides of strand 5. The wire is then continued upwardly and passed inwardly of strand 1, as shown at 14, the previous loop 10 being disposed outwardly of said strand. The wire is then carried outwardly and around strand 2, as shown at 15, then downwardly and inwardly, at 16, of strand 3, then through strands 4 and 7 in juxtaposition with the 10 previously formed loop 17, so that two loops 17 and 18 will be provided at this point which are adapted to be crowded together when the coil is bent to form the inner periphery. The continuing portion of the 15 loop 18 is extended upwardly and inwardly of strand 5, as shown at 19 and in close contact with said strand and in juxtaposition with the previously formed loop 9. The continuing portion of the loop 19 is then 20 extended and carried outwardly of strand 1 to provide loop 20 and in close contact with strand 1. While I have shown the various loops or portions of the turns of wire in certain instances spaced outwardly or inwardly from the strands 1, 2, 3 and 25 5 for the purposes of illustration only, it must be borne in mind that the loops of all the turns are in close contact with the strands so that when the coil is complete, 30 a section of the coil at any point will disclose a circle. The continuing portion of loop 20 of the wire is then carried inwardly of strand 2, forming a loop 21 which is also in contact with said strand. The wire 35 is then continued outwardly and around and in engaging relation with strand 3, as shown at 22. The loop 22 is in juxtaposition with the previously formed loop 12. The continuing portion of loop 22 of the 40 wire is carried downwardly around and outwardly of strand 4, as shown at 23, and adjacent loop 8, thereby contacting with strand 5 to provide loop 24 and then carried inwardly in engagement with strand 1, as shown at 25. The continuing portion of loop 25 is carried outwardly and around strand 2 adjacent loop 15 to form a loop 26. The wire 6 is then interwoven with the 45 strands to provide similarly formed loops, as has been just described, until the coil has been completed, thereby always providing at the inner periphery of the coil a pair of loops 17 and 18 inserted through strands 4 and 7, and a pair of loops 8 and 23 engaging around strand 4 and embracing loops 50 55 8 and 23, so that when the ends of the strands, as shown at 27 and 28, are brought together and tied to form the toroidal coil 29, the loops 8 and 23 may be crushed, as it were, over the loops 17 and 18 and provide for a more compact and uniform inner periphery 30.

By my particular method of weaving, the loops or portions of the turns of wire always cross each other at a supporting strand 70 so that the turns of the coils are securely locked against displacement.

In the preferred form shown in Figures 4 and 5, the wire 40 is interwoven with the supporting strands 41, 42, 43, 44, 45 and a 75 reinforcing strand 46 in a manner similar to the weaving of the strands shown in Figures 2 and 3, with the exception that a pair of loops 47 and 48 are always provided inwardly of the reinforcing strand 46, while 80 a loop 49 is disposed between strands 44 and 46 and a loop 50 is located outwardly of strand 44. It will also be noted that the continuing portions of the loops of the wire 85 alternately cross each other and on opposite sides of the other strands 41, 42, 43 and 45, with the loops always in close contact with the respective strands.

This construction also provides for the 90 economical crowding of the loops 49 and 50 95 and 47 and 48, so that when the coil is formed by bringing the ends of the strands together, the outer loops 49 and 50 may be bent around and in embracing relation to substantially receive the inner loops 47 and 100 48. By reason of the crowding of the loops at the periphery of the toroidal coil, a stronger and better coil is provided, since pairs of loops overlap and embrace other pairs of loops and a smaller diameter of 105 the periphery of the coil is provided for the same number of turns of wire which have been previously employed in the manufacture of the well known forms.

The forming of the pairs of loops having 110 a longer or shorter diameter than alternate pairs provides for the partial reception of the loops having the smaller diameter within the loops of larger diameter and at the inner periphery of the coil, so that the outer 115 loops having the greater diameters will not only partially receive the inner loops but may be bent over the outer edges of the inner loops. With this construction, a more compact coil is provided, since the lessening 120 of the inner periphery of the coil does not require the usual wide spaces between the portions of the loops at the outer periphery of the coil and therefore does not require the usual wide spacing of the turns at the outer 125 periphery of the toroidal coil.

Having thus described my invention, I claim:

1. A toroidal coil formed of spaced flexible supporting strands, and a wire inter-

- woven with the strands to provide loops, alternate pairs of the loops of the wire at the inner periphery of the coil being disposed inwardly of the other pairs of the loops so that the inner pairs of the loops will be received within the outer pairs of the loops.
2. A toroidal coil formed of spaced flexible supporting strands, a reinforcing strand, and a wire interwoven with the strands to provide loops, alternate pairs of loops of the wire at the inner periphery of the coil being disposed inwardly of other pairs of the loops, the reinforcing strand co-operating with an adjacent supporting strand for aiding in spacing the longer loops at the inner periphery of the coil.
3. A toroidal coil formed of spaced flexible supporting strands, a reinforcing strand, and a wire interwoven with the strands to provide loops, the portions of alternate pairs of the loops being disposed upon opposite sides of the reinforcing strand so that the portions of the loops of a pair located inwardly of the strand are adapted to be partially embraced by the pairs of loops located outwardly from the reinforcing strand and at the inner periphery of the coil.
4. A toroidal coil formed of spaced flexible supporting strands, a reinforcing strand, and a wire interwoven with the strands to provide spirally arranged loops, a portion of a pair of loops of the wire being disposed inwardly of the reinforcing strand while the pairs of loops located between the alternate pairs of loops are disposed outwardly of the reinforcing strand.
5. A toroidal coil formed of spaced flexible supporting strands, a reinforcing strand, and a wire interwoven with the strands to provide spirally arranged loops, a portion of a pair of loops of the wire being disposed inwardly of the reinforcing strand while the pair of loops located between the alternate pairs of loops are disposed outwardly of the reinforcing strand, one of the loops of the intermediate pair of loops being disposed between the reinforcing strand and an adjacent supporting strand, the other loop being located outwardly of the supporting strand.
6. A toroidal coil formed of spaced flexible supporting strands, and a wire interwoven with the strands to provide spirally arranged loops, alternate pairs of the loops being of less diameter than the other pairs of loops.
7. A toroidal coil formed of spaced flexible supporting strands, and a wire interwoven with the strands to provide spirally arranged loops, alternate pairs of the loops being of less diameter than the other pairs of loops, one loop of each alternate pair of loops being of less diameter than the adjacent loop of said pair.
8. A method of forming toroidal coils which comprises applying a conducting wire to supporting strands spaced about a longitudinal axis and a reinforcing strand spaced from one of the supporting strands, weaving the wire consecutively above and below alternate strands and placing at the same time a pair of loops of the wire above the reinforcing and alternate pairs of loops below said strand.
9. A toroidal coil formed of spaced flexible strands and a plurality of turns of a wire interwoven with the strands and a reinforcing strand interwoven with the turns and co-operating to place portions of alternate pairs of the turns of the wire at the inner periphery of the coil within the adjacent pairs.
10. A toroidal coil formed of spaced flexible supporting strands, a reinforcing strand, a wire interwoven with the strands to provide spirally arranged loops, a portion of a series of loops of the wire being disposed inwardly of the reinforcing strand while the series of loops located between the alternate series of loops are disposed outwardly of the reinforcing strand.
11. A toroidal coil formed of spaced flexible supporting strands, and a wire interwoven with the strands to provide spirally arranged loops, alternate series of the loops being of less diameter than the other series of loops.
